FIG. 1.

FIG. 2.

Inventor

T. J. Steele

By Watson E. Coleman
Attorney

UNITED STATES PATENT OFFICE.

THOMAS J. STEELE, OF NORFOLK, VIRGINIA.

HANGER.

1,303,409.

Specification of Letters Patent. Patented May 13, 1919.

Application filed January 15, 1919. Serial No. 271,270.

To all whom it may concern:

Be it known that I, THOMAS J. STEELE, a citizen of the United States, residing at Norfolk, in the county of Norfolk and State 5 of Virginia, have invented certain new and useful Improvements in Hangers, of which the following is a specification, reference being had to the accompanying drawings.

This invention relates to certain improvements in hangers, and has relation more particularly to a device of this general character especially designed and adapted for use in connection with swings, hammocks, or other oscillating bodies, and it is an object of 10 the invention to provide a novel and improved device of this general character which permits an oscillation of the body, such as a swing, without noise. It is also an object of the invention to provide a novel 15 and improved device of this general character comprising two relatively movable members one supported by the other and both being in constant interlocking engagement so that the oscillating body, such as a swing, 20 may have its movement with facility and with the substantial elimination of noise which would otherwise result in the event such members were capable of slipping movement one relative to the other.

25 The invention consists in the details of construction and in the combination and arrangement of the several parts of my improved hanger whereby certain important advantages are attained and the device rendered simpler, less expensive and otherwise 30 more convenient and advantageous for use, as will be hereinafter more fully set forth.

The novel features of my invention will hereinafter be definitely claimed.

35 In order that my invention may be the better understood, I will now proceed to describe the same with reference to the accompanying drawings, wherein:

Figure 1 is a view partly in side elevation 40 and partly in section of a hanger constructed in accordance with an embodiment of my invention, a coacting support being indicated by dotted lines; and

Fig. 2 is a view partly in edge elevation 45 and partly in section of my improved hanger as herein disclosed.

As disclosed in the accompanying drawings, 1 denotes a shank adapted to be threaded or otherwise secured to a beam or other support and said shank 1 is provided with a flattened head 2 substantially triangular in

form. The outer end portion of the head 2 has disposed therethrough an opening 3 having its forward wall straight and said wall is provided with a series of inwardly directed teeth 4.

Disposed through the opening 3 is a block 5 having an edge thereof provided with an arcuate rack 6 meshing with the teeth 4 and whereby said block 5 is capable of rocking 65 movement without slipping.

As clearly illustrated in Fig. 2 of the drawings, the block 5 is of a thickness greater than the thickness of the head 2, and the portion of said head 2 below the 70 teeth 4 has its outer faces inwardly beveled as indicated at 7.

H denotes a hook member comprising two substantially duplicate parts connected at a point midway their lengths by the bolt 8 75 and the coacting nut 9. The outer end portions of the parts or sections a are in close contact when said sections or parts a are in operative relation, and the opposite end portion of each of the parts or sections a is outwardly offset as at b and said offset portion overlies a side face of the block 5.

The overlying extremities of the portions b are secured to the block 5 by the bolts 10 disposed through said portions b and the 85 block 5, and coacting with each of the bolts 10 is a clamping bolt 11.

It is to be particularly noted that the opening 3 is of such size that the block 5 can be arranged therein only by movement in a 90 direction laterally of the head 2, and that said opening is also of a size to prevent the rack 6 of the block 5 and the teeth 4 from becoming entirely disengaged so that the proper assemblage of the hanger is assured. 95

This advantageous result is obtained by having the space between the back or upper edge of the block 5 and the corresponding wall of the opening 3 of a width less than the length or pitch of the intermeshing teeth 6 and more particularly when the hanger H is substantially at right angles to the straight wall defining the opening 3. It is also to be understood that the swinging movement of the hook member H relative to the head 2 in either direction is limited by contact of an end portion of the block 5 with an end wall of the opening 3.

From the foregoing description, it is thought to be obvious that a hanger constructed in accordance with my invention 110 is particularly well adapted for use by rea-

son of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown 10 in carrying out my invention in practice except as hereinafter claimed.

I claim:

A hanger of the class described comprising a member provided with a head, said 15 head having an opening, a wall of said opening being provided with inwardly directed

teeth, a block disposed through said opening and provided with an arcuate rack meshing with the teeth, said block being of a size less than the size of the opening, the rear edge of the block and the corresponding wall of the opening being spaced apart a distance less than the length of the teeth of the block, and a hook member having separated parts at an end portion thereof 25 secured to the side faces of the block.

In testimony whereof I hereunto affix my signature in the presence of two witnesses.

THOMAS J. STEELE.

Witnesses:

TH. M. GIRAUD,
G. T. ELLIOTT.
